W. W. McCARROLL

ELECTROTYPER'S CASE

Filed Jan. 5, 1924

Inventor

Walker W. McCarroll,

By *W. W. McCarroll*

Attorney

UNITED STATES PATENT OFFICE.

WALKER W. McCARROLL, OF NEW HAVEN, CONNECTICUT.

ELECTROTYPER'S CASE.

Application filed January 5, 1924. Serial No. 684,672.

To all whom it may concern:

Be it known that I, WALKER W. McCARROLL, citizen of the United States, residing at New Haven, in the county of New Haven and State of Connecticut, have invented certain new and useful Improvements in Electrotypers' Cases, of which the following is a specification.

This invention relates to certain new and useful improvements in electrotypers' cases.

Heretofore electrotypers' cases have been formed of lead plates or sheets owing to the property of the lead in resisting the action of the acid in the electrolytic solution, the sheets or plates being faced with a coating of beeswax, a mixture of ozokerite or a composition of equivalent density. The objections experienced by electrotypers to the use of a lead plate are manifold and among 20 which may be briefly mentioned the difficulty of maintaining the plate in a plane for molding; the tendency of the lead to jam on its edges in handling and the constant necessity of straightening by highly skilled labor 25 through use of a planer and mallet to maintain the plate in as near a proper condition as possible, the expense of melting, recasting, boring of holes and planing when the case becomes unfit for further use.

The primary object of the present invention therefore is to overcome all of the above objections and to also provide a case which is of reduced weight so as to increase production by facilitating handling in the various operations of wax-casting, shaving, molding, building-up, black-leading, preparation for the tubs, and stripping the shell from the case after deposition of the copper.

The invention briefly, also aims to enable 40 larger and thicker cases to be used without unduly increasing the exertion required in handling and to overcome the tendency of the connection hooks to break through the side of the case, with consequent destruction 45 thereof.

Other and further objects will be later more specifically mentioned and of themselves manifested in the course of the following description.

In the drawings:

Figure 1, is a top plan view of the invention;

Figure 2, is a section on line 2—2 of Figure 1;

Figure 3, is a fragmentary plan view of 55 the plate after preparation for and prior to the application of the wax facing, and

Figure 4, is a view similar to Figure 3, of a modified form of the invention.

In proceeding in accordance with the present invention a plate 1 formed of hard rolled aluminum is employed. Owing to the extreme hard and smooth properties of the aluminum sheet, it is necessary to prepare a side face thereof for the reception of the 60 melted wax 2 so as to effect adherence thereof to the sheet. This may be accomplished in various manners, for example by filing or mechanically roughing the face as shown at 65 3 in Figure 4, or by chemically granulating 70 or stippling the face as shown at 4 in Figure 3, for example by application of hot lye. The latter method has in actual practice been found the most expeditious and economical. The melted wax is now applied to 75 the prepared face of the aluminum plate and forms a coating or layer thereon as depicted in the drawings. The plate is provided with the customary apertures 5 to receive the 80 usual electrical connection hooks.

By the use of the present invention, a marked reduction in weight of the case is had. Lead cases i. e., cases made of lead and other metals, such as tin and antimony 85 weigh about twenty-four (24) pounds, while cases made in accordance with the present invention weigh eight (8) pounds, a difference of sixteen (16) pounds. This factor alone is of vital importance in increased 90 production, an increase of thirty-five percent (35%) having been attained in actual test, since a case passes through upwards of seven stages of operation by as many men, to wit: the wax caster, the shaver and 95 flasher, the moulder, the builder-up, the black-leader, the wet-leader, the stopper-out, the battery-man, the case-stripper, and the man who melts off the wax, at which point the operations are repeated.

It is also essential that the case be in a 100 perfect plane for the work. When lead cases are used, they get out of shape in handling and must be straightened by using a mallet and planer, which is a highly-skilled 105 operation and even when the operator possesses the highest skill is not always done as well as it should be. The hammering with mallet and planer to preserve the plane

was found to have a tendency to crystallize the metal, and cause it to crack, stretch out of shape and break. The added weight when a case was made larger or thicker greatly increased the danger of the connection hooks breaking through the edge of the case. Both of these causes shortened the life of the lead case, which averages about three months. Cases formed in accordance with the present invention have been in constant use for nearly eighteen months and during that time it has not been found necessary to use a mallet and planer on any one of same.

Cases made of copper and brass have been made in an endeavor to overcome the objections of the lead case. These seemed to have a tendency to reverse the current when a short circuit was formed. They also had a marked tendency to deposit on the back of the case; when this occurred, it was found impossible to strip the deposit from the back, as can be done from a lead case, and the use of copper and brass was discontinued.

Another desirable result secured by the light weight of the case is the fact that the thickness and size of the case can be materially increased without unduly increasing the exertion of the different men handling them. Also when it was endeavored to increase the size of the cases, it was also found necessary to increase the thickness of the plate to better keep it in a plane. The addition of both size and thickness added so much to the weight that they were abandoned except where the size was the essential factor. An increase in size results in a proportionate increase in the quantity produced with but little additional increase in labor.

In practise, I have found that I can secure 35% increase in the production from one case, at an additional expense of less than 15% for labor, and this increase is due entirely to the reduced weight of the case. While the trade has long appreciated the desirability of using large cases, it was found that the labor of handling the larger lead cases was too much of a strain on the operators and tired them so much that their work was slowed down to a point where the

advantage gained by the larger case was lost.

When lead cases are used, at the operation of stripping the shell from the wax, the case is usually set on the floor on one end, and the corners and edges become jammed. This prevented the back of the case from lying flat on the table when the melted wax was poured on the face, and as a result, the wax would flow under the case and extra labor was necessary to remove this wax from the back. The extreme lightness of a case constructed in accordance with this invention is quite a factor in preventing this trouble as it is evident that a lighter case will not be handled as roughly as a heavier one, a reduction in weight assisting greatly in removing the tendency to jam on the edges and corners when placing the case on the floor.

Further when lead cases are used, there is a decided tendency for the holes for the connection hooks to break through the side of the case, destroying its value and necessitating its being melted and recast as a new case, which is avoided by use of the present invention.

Preferably the marginal or edge portions of the wax facing are beveled as depicted in the drawings at 6.

What is claimed is:

1. An electrotyper's case formed of a hard-rolled aluminum plate.
2. An electrotyper's case formed of a hard-rolled aluminum plate having a roughened side face and a coating of wax applied to said roughened face.
3. An electrotyper's case formed of a hard-rolled aluminum plate, and means to affix a coating of wax to a side face of the plate.
4. An electrotyper's case formed of a hard-rolled aluminum plate, and means to affix a coating for receiving the impression to a side face of the plate.

5. An electrotyper's case including a hard-rolled aluminum element and means to affix a coating of material capable of receiving an impression to a side face thereof.

In testimony whereof I affix my signature.
WALKER W. McCARROLL.
